United States Patent Office

Des. 196,455
Patented Oct. 1, 1963

196,455

FRAGRANCE BOTTLE

Walter Stern, New Rochelle, N.Y., assignor to Ondine
Parfums Inc., Miami, Fla., a corporation of Florida

Filed Aug. 14, 1962, Ser. No. 71,280

Term of patent 14 years

(Cl. D58—8)

I claim:

The ornamental design for a fragrance bottle, as shown.
